UNITED STATES PATENT OFFICE.

JAMES T. CLARK, OF MILWAUKEE, WISCONSIN; MARY F. CLARK ADMINISTRATRIX OF SAID JAMES T. CLARK, DECEASED.

RAILWAY SPLICE-BAR.

SPECIFICATION forming part of Letters Patent No. 403,251, dated May 14, 1889.

Application filed July 15, 1886. Serial No. 208,089. (No model.)

To all whom it may concern:

Be it known that I, JAMES T. CLARK, of the city and county of Milwaukee, and State of Wisconsin, have invented certain new and useful Improvements in Railway Splice-Bars; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

My invention relates to the "splice-bars" or "fish-plates" employed to unite the adjacent ends of railway-rails, and their combination with the rails, which they support and unite; and it consists, essentially, in giving those splice-bars a particular form and proportion, fitting them for the purpose designed to be accomplished by them.

The object of my invention is to secure a railway-track which shall have a uniform vertical resistance and flexibility, so that the track shall be as nearly as possible in that respect what it would be if the rails were continuous throughout their length, instead of being formed of separate rails joined by mechanical connections.

It is well known that absolute rigidity in railroad-rails is undesirable, as it would produce greater vibration and thereby injure both the rolling-stock and the rails themselves. There is a certain amount of vertical deflection in every rail under the weight of a passing train-wheel, which deflection travels along the rail like waves on the surface of water. If the rail be uniformly vertically flexible, this wave of deflection will be of constant depth, and consequently the wheel will move in a horizontal line, notwithstanding the yielding of the rail; but if the rail be of unequal stiffness, the moving wheel must drop at the weakest points and rise at the stiffer points, and thereby the same effect would be produced that would be found to result from inequalities in the upper surface of the rail. To avoid such difficulties, I secure uniform flexibility in the line of united rails by making the splice-bars of increasing thickness and

stiffness, so as to compensate for the decreasing stiffness of the rail as its end is approached, and also by making the thickness and stiffness of the splice-bar decrease with the increasing stiffness of the next rail as its extremity is receded from. I accomplish this by making the splice-bars thickest at their centers, which are opposite the ends of the rails, and making them taper therefrom toward their extremities, as hereinafter shown.

In the accompanying drawings, Figure 1 is a side elevation of my improved device. Fig. 2 is a horizontal longitudinal section thereof, on the line *x* *x* in Fig. 1, and Fig. 3 is a transverse vertical section on the line *y* *y* in Figs. 1 and 2.

A *A* are two adjacent rails. *B* is the joint between them.

C *C* are my improved splice-bars, the form and construction of which are shown in the several figures. I prefer to form them with a base-flange, *n*, resting on the ties in the same plane with the base of the rail and outside of the outer edges of the same; but this is not essential, as I may employ splice-bars without such a lower flange. The upper edge and lower inside edge of the splice-bars are fitted to the head and base of the rail, as shown at *i* *i* and *k* *k*, Fig. 3, in the usual manner.

The upright flange *H* of the splice-bar, and the bar itself when the lower flange, *n*, is discarded, is tapered lengthwise, as shown in horizontal section in Fig. 2.

The size of the splice-bar and extent and degree of taper must of course be proportioned to the size of the rail employed.

For use with a rail weighing fifty-six to sixty-seven pounds per yard, I make the splice-bars forty inches long, seven-eighths of an inch thick at the center, and seven-sixteenths of an inch thick at the ends of the upright or tapered flange *H*. The taper is nearly uniform, or, as I prefer to make it, the arc of a circle with thirty-eight feet radius, passing through two given points forty inches apart, and the other or inner line of the horizontal section of the tapered flange is a straight line drawn parallel to the chord of the arc and seven-sixteenths of an inch nearer the center of the circle from which the arc is struck.

The splice-bar is perforated at *e e* for fastening-bolts *d d* in the usual way, and also notched at *s s* when formed with the base-flange *n* for the spikes.

5 The special form of my splice-bar may be varied without departing from the principle of my invention or its general construction.

I consider it essential, however, that the splice-bar should taper with approximate regularity from its center toward each end.

I construct my splice-bar of wrought or rolled iron or steel, so as to make it flexible, like the rail to which it is applied.

I claim—

15 1. An elastic railway splice-bar, of wrought or rolled metal, tapering uniformly, or nearly so, from its center to its extremities, and provided with the usual means of fastening to the rails, substantially as and for the purposes set forth.

20 2. The combination of two railway-rails and

one or more elastic splice-bars, tapering uniformly, or nearly so, from their center to their extremities, so as to make the wave of deflection of continuously uniform depth, or nearly so, and provided with the usual means of attachment to the rails, substantially as and for the purposes set forth.

3. An elastic railway splice-bar, of wrought or rolled metal, tapering uniformly, or nearly so, from its center to its extremities, and provided with the usual means of fastening to the rails, and having its inner wall straight, substantially as and for the purposes set forth.

In testimony that I claim the foregoing as my own I affix my signature in presence of two witnesses.

JAMES T. CLARK.
